UNITED STATES PATENT OFFICE.

CHARLES H. BARR, OF PITTSBURG, PENNSYLVANIA.

COMBINATION-TOOL.

SPECIFICATION forming part of Letters Patent No. 288,397, dated November 13, 1883.

Application filed June 27, 1883. (No model.)

To all whom it may concern:

Be it known that I, CHARLES H. BARR, of Pittsburgh, in the county of Allegheny and State of Pennsylvania, have invented certain new and useful Improvements in Combination-Tools; and I do hereby declare that the following is a full, clear, and exact description of the invention, which will enable others skilled in the art to which it appertains to make and use the same, reference being had to the accompanying drawings, which form a part of this specification, in which—

Figures 1 and 2 are elevations respectively showing the tool in closed and open position.

This invention relates to the construction of a combination-tool which, while adapted generally for various purposes, is especially designed for use in erecting wire fences.

The invention consists in the construction and arrangement thereof, as hereinafter fully described and claimed.

In the drawings, A and B designate the respective parts, united by the pivot-pin *c*, both being preferably steel castings, and pin *c* bedded in one of the parts in casting the same. The portions *d e* are handles for the tool, and handle *e* is formed with a hole, *f*, to receive a ring, *g*. Part A, beneath pin *c*, is formed with the eccentric *h*, and below this the part B has a flange, *i*, the space between *h* and *i* being adapted to receive a wire. Upon closing the handles the eccentric *h* binds with great pressure upon the wire and gives a grip for stretching the same. Such grip is strengthened by the strain on the wire, which tends to draw the eccentric into closer contact with the wire. Part A is also formed with a nipper-jaw, *k*, and part B has a similar jaw, *l*, lapping over laterally, so as to operate in the same plane as jaw *k*. Under the jaw *l* part B has the recess or slot *m*, and the two parts A and B are formed with the cutting or shearing edges *n*, as shown, close to the pivot-pin *c*, so as to have great power for cutting. In each

of the jaws *k l* is formed a transverse groove, *p*, whose purpose is to grip a wire for bending and shaping.

The whole device, except pin *c* and ring *g*, is of cast-steel, and after casting nothing is required except to grind up the meeting faces slightly to make a fit and to bore out one of the parts to receive pin *c*, and then rivet up the pin. Any desired temper may be given the cutting and nipping parts.

The object of the ring *g* is to enable the application to be made of a lever or crowbar in erecting fences. The lever is passed through the ring after the fencing-wire is in the grip of the eccentric *h i*, and fulcrumed either on the ground or back of the fence-post, and thus the wire may be stretched to any degree of tautness.

The whole tool is simple and very cheap. While designed especially for wire-fence construction, it becomes a convenient tool for various purposes about a farm, and can be used for cutting wire, &c., and as pinchers or nippers.

I claim as my invention—

1. The combination-tool composed of the two parts A B, pivoted at *c*, part A having convex surface *h* and jaw *k*, and part B having flange *i* and jaw *l*, and each jaw provided with a shearing-edge, *n*, substantially as described.

2. The combination-tool composed of the two parts A B, pivoted at *c*, part A having convex surface *h* and jaw *k*, and part B having flange *i*, jaw *l*, and ring *g*, and each of said jaws provided with a shearing-edge, *n*, substantially as described.

In testimony that I claim the foregoing as my own I have hereto affixed my signature in presence of two witnesses.

CHARLES H. BARR.
